BROAD RUNG LADDER

Noël L. Dahlander, New York, N. Y., assignor of
one-half to Robert J. Earl, New Canaan, Conn.

Application May 14, 1943, Serial No. 486,970

16 Claims.

(Cl. 228—40)

This invention relates to flexible ladders in general and more especially to flexible chain ladders of the type extensively used in connection with sea-going vessels and known as Jacob's ladders.

Among the objects of the present invention it is aimed to provide an improved flexible ladder provided with rungs that only have an extended tread or gripping surface constituting the rung for the foot of the user, but which rung will be anchored in position for use thereby materially reducing the hazards encountered in using these ladders, especially when disembarking from a vessel in case of distress due to an explosion, a fire or the like.

It is still another object of the present invention to provide an improved flexible ladder provided with rungs composed initially mainly of wood or the like material not dangerous to the bare hands of a user in extreme low temperatures, but also in part composed of metal, so that should one or the other wooden portion be destroyed in fire or the like, the ladder would still be usable.

Specifically, the invention aims to provide an improved flexible ladder, composed essentially of two parallel flexible members for each suspensory element, a set of broad treads or rungs connected to said suspensory elements and composed not only of a metal extension, but also of one or more wooden or the like buoyant extensions anchored by said suspensory elements against displacement relative to one another when in use, and spacer plates at the ends of the rungs extending the full width of the rungs.

These and other features, capabilities and advantages of the invention will appear from the subjoined detailed description of one specific embodiment thereof illustrated in the accompanying drawing in which

Figure 1 is a fragmental elevation of a ladder made according to the present invention.

Fig. 2 is a fragmental end elevation of the same.

Fig. 3 is a fragmental enlarged detail in end elevation, particularly showing one of the spacer plates.

Fig. 4 is a section on the line 4—4, of Fig. 3.

Fig. 5 is a section on the line 5—5 of Fig. 3.

Fig. 6 is a perspective of one of the connecting clips for connecting the suspensory elements, rungs and spacer plates to one another.

Fig. 7 is a fragmental detail showing the connection between the metal part of a rung and a spacer plate.

In the embodiment shown, there is illustrated a single ladder as distinguished from a multiple ladder, although obviously the main features of the invention would be applicable to a multiple ladder as well as to a single or Jacob's ladder. The single ladder shown is illustrated as composed of two flexible members for each longitudinally extending suspensory element 1, 2. In the present instance each of the flexible members 3, 4, 5 and 6 is composed of a chain, the links of which are typical of the lock-link pattern and arranged preferably with the free loop of the link, such as the link 7, at the bottom, and the interconnected end portions 8 and 9 of such link 7 at the top. The uppermost link 10 of each chain is preferably reversed as compared to the position of the link 7 with its free loop at the top and its twisted ends 11 and 12 at the bottom spaced apart to receive between them the twisted ends 8 and 9 of the adjacent lower link as shown in Fig. 2 to register with one another and receive a rivet or pin 13, as shown in Figure 1. The upper free loop 12 as shown in Figs. 1 and 2 is preferably provided with a protecting shield 14 to engage the connecting ring 15 as shown. In other words, each of the chains 3, 4, 5 and 6 has, at its upper end, a link 10 received by the ring 15 as shown. The ring 15 is provided, of course, to receive a lash or other fastening means for connecting the upper ends of the ladder in the usual way.

In the present instance the two chains 3 and 4 are connected to one ring 15 and the two chains 5 and 6 connected to another ring 15. The two chains 3 and 4 as they extend downwardly are spread apart and so maintained by their connection with the spacer plate 16 and the chains 5 and 6 gradually spread away from one another as they descend from the ring 15 to be spaced apart by their connection with the spacer plate 17. From the spacer plate 16 to the succeeding spacer plates 18, the chains 3 and 4 are maintained substantially parallel, and similarly the chains 5 and 6 as they extend from the spacer plate 17 to the succeeding spacer plates 19.

The connection of the chains 3, 4, 5 and 6 with the rungs and the construction of the rungs now to be described constitutes the main part of the present invention.

Each rung 20 consists essentially of a number of extensions, one composed of wood or the like low heat conducting material such as the rung elements 21 and 22, and the other of metal or the like fire resisting material such as rung element 23. The elements of this divisible rung

construction are normally anchored against displacement relative to one another, as a result of their cooperation with the multiple chain suspensory elements. The rungs 20 during ordinary weather conditions present a broad tread for the user. The rung element 21, composed of wood or the like low heat conductive material is provided so that in extreme low temperatures, as compared to rungs composed of metal, the users are protected from the ordinary hazards encountered when, as an instance, the user is required to engage the rung with his bare hands. On the other hand, rung element 23 composed of metal or the like, serves as an emergency rung, should the portion such as the rung elements 21 and 22 be destroyed, consumed or otherwise impaired by a fire or the like.

For anchoring the spacer plate 16 to the chains 3 and 4 and to the rung elements 21, 22 and 23, and also to connect the plate 17 to the chains 5 and 6 and to the rung elements 21, 22 and 23, the construction now to be described is preferably employed. Since this connection is identical, the connection between the plate 17 and the chains 5 and 6 and the rung elements 21, 22 and 23 will alone be described.

In the first place, all of the spacer plates, such as the spacer plate 17, are provided with an inwardly turned flange 24 extending away from the adjacent suspensory element. In the next place, each spacer plate, such as the spacer plate 17, is grooved at the ends 25 and 26 as shown, and the length of each plate as compared to its width is substantially two to one. Preferably when three rung elements are used as the rung elements indicated, to wit, 21, 22 and 23, two oblong openings are provided, such as the opening 27 snugly to receive the diminished end 28 of the element 21, which end 28 is oblong in cross section. The diminished end 29 of the element 22 is similarly oblong in cross section. These two oblong openings 27 are disposed to either side of the substantially round opening 30 to receive the end of the metal element 23, in the present instance shown as cylindrical or tubular in construction. The end of the element 23 is forced through the opening 30 to project a short distance therebeyond and preferably lapped over or burred as shown by the bur 31 and the outer face of the element 23 nicked, as shown at 32 and 33, so that a portion of the metal will flow out and form the shoulders 34 and 35. The wood rung elements 21 and 22 will thus be effectively anchored in position by so locking the metal element 23 at both of its ends to the spacer plates 16 and 17. However, further to anchor the wooden rung elements 21 and 22 in place, there are provided the screws 36 and 37 which extend through the clips 38 and 39, respectively, and into the diminished ends 28 and 29 as shown in Fig. 4. The clips 38 and 39, see Fig. 6, are provided with an intermediate web portion 40, and two parallel webs 41 and 42 provided with extensions 43 and 44 at the end of the web 41, and extensions 45, 46 at the end of the web 42. The spacer plate 17 is provided with four openings to receive the rung elements 43, 44, 45 and 46, these rungs elements 43, 44, 45 and 46 being long enough to be bent over on the inner face of the spacer plate 17 as shown in Fig. 4, the webs 41 and 42 corresponding in width to the length of the diminished end 28 beyond the plate 17, which end 28 in turn corresponds to the distance between the inner face of the spacer plate 17 and the outer surface of the main loop of the link 47, allowing, see Fig. 5, for the space

formed by the upper looped ends of the link 47 and the upper looped ends of the next succeeding lower link 48. In supporting position, the edge of the web 40, see Fig. 5, will rest on the upper looped ends of the link 48 immediately beneath the same. The web 40 as shown in Fig. 5 also will engage the outer face of the main loop of the link 47 located in the clip 38.

From the foregoing it will be seen that in extremely cold weather the outer rung elements 21 or 22 will be free to be grasped by the hands of the user so that there is no occasion for the user to engage the metal element 23.

On the other hand, due to the connection as aforesaid, should the wooden portions 21 and/or 22 be consumed or impaired by fire, the suspensory elements 1 and 2 will still be anchored in place by the clips 38 and 39 relative to the metal portion 23 of the rung, and consequently, while not as effective, yet an emergency rung will be presented for use.

Furthermore, in ordinary use, when all three rung elements 21, 22 and 23 are intact, due to the connection of these rung elements with the spacer plates 16 and 17 and the multiple suspensory elements 1 and 2, a broad tread for the user will be presented greatly to facilitate climbing up or down this ladder, especially when the user is encumbered with a heavy pack, as an instance, a man under arms or the like.

In the present instance, the spacer plates 16 and 17, therefore, not only serve to space the ladder from the side of the vessel during use, but also to make possible the connection of multiple suspensory elements to multiple tread members.

Preferably the outer rung elements 21 and 22 have a greater thickness than the intermediate rung element 23, good results having been achieved when the diameter of the outer rung elements 21 and 22 is at least twice the diameter of the intermediate rung element 23 to enable the user to avoid contacting the intermediate rung element 23 in extremely cold weather.

It is obvious that various changes and modifications may be made to the details of construction without departing from the general spirit of the invention as set forth in the appended claims.

I claim:

1. The combination of a plurality of freely movable flexible longitudinally extending suspensory members, multi-part broad rungs, and means including spacer plates connecting two of the suspensory members to the ends of each of said rungs in turn to anchor the several parts of each rung against displacement relative to one another, the rungs being connected to extend inwardly from the inner faces of said plates and the suspensory members being connected to extend along the outer faces of said plates, and the spacer plates in turn maintaining the suspensory members spaced from one another throughout their lengths.

2. The combination of a plurality of freely movable flexible longitudinally extending suspensory members, multi-part broad rungs, and means including spacer plates connecting at least two of the suspensory members to each end of a rung in turn to anchor the several parts of each rung against displacement relative to one another, the parts of each rung being connected to extend spaced from one another inwardly from the inner faces of said plates and the suspensory member being connected to extend spaced from one another throughout their lengths along the outer faces of said plates.

3. In a ladder, the combination of suspensory elements, each suspensory element composed of several longitudinally extending flexible members, transversely extending multi-part rungs, and means including spacer plates for spacing the ladder from the side of the structure with which it is being used and also connecting the suspensory elements and rungs to one another in turn to anchor the several parts of each rung against displacement relative to one another, the flexible members of each suspensory element being spaced from one another by said spacer plates throughout their lengths.

4. In a ladder, the combination of suspensory elements, each suspensory element composed of a plurality of chains, transversely extending multi-part rungs, and means including spacers for spacing the ladder from the side of the structure with which it is being used and also connecting the suspensory elements and rungs to one another in turn to anchor the parts of each rung against displacement relative to one another, the chains of each suspensory element being spaced from one another by said spacers throughout their lengths, and certain links of each chain being connected to the outer face of a spacer to enable the chain otherwise to be movable relative to said spacer.

5. In a ladder, the combination of suspensory elements, each suspensory element composed of two chains, transversely extending multi-part rungs, and means including spacers for spacing the ladder from the side of the structure with which it is being used and also connecting the suspensory elements and rungs to one another, said means connected to said chains to space the chains of each suspensory element from one another and also connected to the several parts of each rung to space them alongside of one another in a transverse direction.

6. In a ladder, the combination of suspensory elements, each suspensory element composed of a plurality of longitudinally extending metal flexible members, transversely extending multi-part rungs, each rung having one rung element composed of a fire resistant material such as metal and another independent rung element composed of a material of low heating conductivity such as wood, and means including metal spacers for spacing the ladder from the side of the structure with which it is being used and also connecting the suspensory elements and rungs to one another, said means connected to said chains to space the flexible members of each suspensory element from one another and also connected to the several rung elements of each rung to space them along side of one another in a transverse direction.

7. In a ladder, the combination of suspensory elements, each suspensory element composed of a plurality of longitudinally extending metal flexible members, transversely extending multi-part rungs, each rung having an intermediate narrow rung element composed of a fire resistant material such as metal and two outer broad independent rung elements composed of a material of low heat conductivity such as wood, and means including metal spacers for spacing the ladder from the side of the structure with which it is being used and also connecting the suspensory elements and rungs to one another, said means also spacing the flexible members of each suspensory element from one another and spreading the several rung elements of each rung alongside of one another in a transverse direction.

8. The combination of suspensory elements,

each suspensory element composed of a plurality of longitudinally extending metal flexible members, transversely extending multi-part rungs, each rung having an intermediate rung element composed of fire resistant material such as metal and two outer independent rung elements composed of a material of low heat conductivity such as wood, metal spacers, there being openings in said spacers to receive the ends of said metal rung elements, said metal rung elements being upset in part to either side of said spacers to anchor said metal rung elements in place, metal clips connected to said spacers and embracing parts of said flexible members, and screws connecting said clips to said wood rung elements.

9. The combination of suspensory elements, each suspensory element composed of a plurality of longitudinally extending metal flexible members, transversely extending multi-part rungs, each rung having an intermediate rung element composed of fire resistant material such as metal and two outer independent rung elements composed of a material of low heat conductivity such as wood, metal spacers, there being openings in said spacers to receive the ends of said metal rung elements, said metal rung elements being upset in part to either side of said spacers to anchor said metal rung elements in place, there being oblong openings in said spacers to either side of said metal rung element, oblong diminished ends on said wood rung elements extending into the oblong openings in said spacers, and metal clips connected to said spacers and embracing parts of said flexible members to anchor the same in place.

10. The combination of suspensory elements, each suspensory element composed of a plurality of longitudinally extending metal flexible members, transversely extending multi-part rungs, each rung having an intermediate rung element composed of fire resistant material such as metal and two outer independent rung elements composed of a material of low heat conductivity such as wood, metal spacers, there being openings in said spacers to receive the ends of said metal rung elements, said metal rung elements being upset in part to either side of said spacers to anchor said metal rung elements in place, there being oblong openings in said spacers to either side of said metal rung element, oblong diminished ends on said wood rung elements extending into the oblong openings in said spacers, metal clips connected to said spacers and embracing parts of said flexible members to anchor the same in place, and screws connecting said clips to said wood rung elements.

11. The combination of suspensory elements, each suspensory element composed of a plurality of longitudinally extending chains composed of links, each link having its free ends interlocked at one end with an adjacent link, transversely extending multi-part rungs, each rung having an intermediate rung element composed of fire resistant material such as metal and two outer independent rung elements composed of a material of low heat conductivity such as wood, metal spacers, there being openings in said spacers to receive the ends of said metal rung elements, said metal rung elements being upset in part adjacent both faces of said spacers to anchor said metal rung elements in place, and metal clips connected to said spacers and embracing parts of said chains intermediate the interlocking ends of their links to anchor the chains in place.

12. The combination of suspensory elements, each suspensory element composed of a plural-

ity of longitudinally extending chains composed of links, each link having its free ends interlocked at one end with an adjacent link, transversely extending multi-part rungs, each rung having an intermediate rung element composed of fire resistant material such as metal and two outer independent rung elements composed of a material of low heat conductivity such as wood, metal spacers, there being openings in said spacers to receive the ends of said metal rung elements, said metal rung elements being upset in part adjacent both faces of said spacers to anchor said metal rung elements in place, there being openings in said spacers to either side of said metal rung element, and metal clips having projections extending through said latter openings and upset in part to anchor the clips in place, said clips embracing parts of said chains intermediate interlocking ends of the links to anchor the chains in place.

13. The combination of suspensory elements, each suspensory element composed of a plurality of longitudinally extending metal flexible members, transversely extending multi-part rungs, each rung having an intermediate rung element composed of fire resistant material such as metal and two outer independent rung elements composed of a material of low heat conductivity such as wood, metal spacers, there being openings in said spacers to receive the ends of said metal rung elements, said metal rung elements being upset in part to either side of said spacers to anchor said metal rung elements in place, metal clips connected to said spacers and embracing parts of said flexible members, and screws connecting said clips to said wood rung elements, said spacers consisting of oblong plates having inwardly extending flanges.

14. The combination of flexible longitudinally extending suspensory members, each suspensory

member including two chains, multi-part broad rungs, each broad rung including two rung elements, and means including spacer plates connecting the suspensory members and rungs to one another in turn to anchor the several parts of each rung against displacement relative to one another, said spacer plates being oblong in shape and having inwardly extending flanges and said means securing one link of each chain and a rung element of each broad rung to a spacer plate with the rung elements of each rung spaced from one another and the chains of each spacer element similarly spaced from one another throughout their lengths.

15. In a ladder, the combination of suspensory elements, each suspensory element composed of two chains, transversely extending multi-part rungs, each rung including two rung elements, spacer plates, and means securing one link of each chain and a rung element of each rung to a spacer plate with the rung elements of each rung spaced from one another and the chains of each suspensory element similarly spaced from one another throughout their lengths.

16. In a ladder, the combination of suspensory elements, each suspensory element composed of two chains, transversely extending multi-part rungs, each rung including two wood rung elements and an intermediate metal rung element, spacer plates, said metal rung elements secured to said spacer plates, and means securing one link of each chain and a wood rung element of each rung to a spacer plate with the wood rung elements of a rung spaced from one another and the chains of each suspensory element similarly spaced from one another throughout their lengths.

17. In a ladder, the combination of suspensory elements, each suspensory element composed of two chains, transversely extending multi-part rungs, each rung including two wood rung elements and an intermediate metal rung element, spacer plates, said metal rung elements secured to said spacer plates, and means securing one link of each chain and a wood rung element of each rung to a spacer plate with the wood rung elements of a rung spaced from one another and the chains of each suspensory element similarly spaced from one another throughout their lengths.

NOËL L. DAHLANDER.
